UNITED STATES PATENT OFFICE.

MERRITT HUTTON, OF ST. BENEDICT, PENNSYLVANIA, ASSIGNEE TO REMBRANDT PEALE, OF NEW YORK, N. Y.

CAR-HAULING MECHANISM.

Application filed August 24, 1920. Serial No. 405,699.

To all whom it may concern:

Be it known that I, MERRITT HUTTON, a citizen of the United States, residing at St. Benedict, in the county of Cambria and 5 State of Pennsylvania, have made certain new and useful Improvements in Car-Hauling Mechanism, of which the following is a specification.

The invention relates to an automatically 10 operating car handling mechanism, and in certain of its features more especially to such mechanism adapted for handling the loaded and empty cars upon a mine dump and in other like places.

15 Objects and advantages of the invention will be set forth in part hereinafter and in part will be obvious herefrom, or may be learned by practice with the invention, the same being realized and attained by means 20 of the instrumentalities pointed out in the appended claims.

The invention consists in the novel parts, combinations, arrangements, and improvements herein shown and described.

25 The accompanying drawings, referred to herein and constituting a part hereof, illustrate one embodiment of the invention, and together with the description, serve to explain the principles of the invention.

30 Of the drawings:

Fig. 1 represents a section of a track and of the automatically operating car handling mechanism and a car being propelled thereby;

35 Fig. 2 is a detail side elevation of the car engaging and propelling device;

Fig. 3 is a horizontal section taken through the device of Fig. 2, on the line 3—3, looking in the direction of the arrows;

40 Fig. 4 is a vertical transverse section taken on the line 4—4 of Fig. 2, looking in the direction of the arrows;

Fig. 5 is a horizontal section, on a reduced scale, taken on line 5—5 of Fig. 2, and showing the car propelling device passing around a curve;

Fig. 6 is a transverse vertical section, taken on the line 6—6 of Fig. 1, looking in the direction of the arrows;

50 Fig. 7 is a plan view, largely diagrammatic, showing tracks for trains of full and empty cars, and an automatic car handling mechanism installed for each track;

Fig. 8 is a greatly enlarged view, partly 55 in plan and partly in horizontal section, of

the driving mechanism and quick return mechanism, for the automatic car handling system or apparatus, said mechanism being shown in its relation to the cars and track in Fig. 7;

Fig. 9 is a full elevation, looking at the mechanism of Fig. 8 from the opposite or top side thereof;

Fig. 10 is a diagrammatic elevation, taken substantially on line 10—10 of Fig. 7, but not necessarily corresponding either as to scale or gradients, showing the dump for the loaded cars and the return track for the empty cars;

Fig. 11 is a top plan of the car-operated 70 automatic control for the driving mechanism for the car-propelling means;

Fig. 12 is a vertical section, greatly enlarged, taken on line 12—12 of Fig. 11; and

Fig. 13 is a diagrammatic plan of another 75 arrangement of the car handling mechanism employing only one power mechanism for both the tracks for the full and the empty cars.

Fig. 14 is a detached detail in plan, of one 80 of the trip levers.

The invention provides novel mechanism for handling cars along tracks and in certain of its features more particularly for handling the full and empty cars on a mine 85 dump, receiving a train or "trip" of full cars and running them one at a time to the dump and returning the empty cars to be made up into a train or "trip" on another track to be returned into the mine. 90

As a part of the foregoing, the invention provides a novel and highly efficient form of car engaging and propelling device, adapted to feed or propel the loaded cars forwarded as required for dumping, and 95 for feeding or propelling the empty cars along an inclined track to bring them to grade on a storage or train making track, to be returned to the mine.

The invention provides further for a relatively slow or gradual forward travel of the car engaging and propelling mechanism or device and for a relatively quick return thereof on its idle trip in the opposite direction. According to one feature of the invention, the driving mechanism for the car propelling mechanism and the quick return therefor are automatically operated by the propelling mechanism reaching a given or predetermined place or point in its travel. 100 105 110

Other features of the invention will be set forth in connection with the following detailed description of the illustrated embodiment.

5 Referring preliminarily to the general features of the embodiment of the invention, illustrated by way of example in the accompanying drawings, a novel car engaging, and propelling device is provided
10 adapted to run upon and to be held down by a single rail, preferably of I beam form. This car propelling device is connected at each end to a cable, which is adapted to draw the device in either direction, that is, either backwardly or forwardly.

15 As herein embodied there are two cables attached, as above stated one to each end of the car propelling device, and they are also wound, respectively over or about two drums, one drum winding on the other drum paying off in one direction, and operating reversely in the opposite direction of travel of the car propelling device.

20 A single motor drives both the drums, and a clutch mechanism is provided which reverses the direction of rotation of the drums. This clutch is preferably operated or controlled, either directly or indirectly, by the car propelling device reaching a certain place or point along the trackway and the device is thus rendered automatic to successively reverse the direction of travel of the car propelling device.

25 The relatively slow advance movement, and the relatively quick return on the idle trip, of the device, are effected preferably through the gear ratios between the motor and the respective drums. This is entirely practicable with high speed on the return trip due to the absence of load.

30 The tracks are arranged preferably with a very slight gradient for a long train of loaded cars whereby a single car propelling device engaging the rear car will gradually progress or propel the entire train slowly forwardly, the foremost car being successively detached and run forward over the dump, and after being dumped and being run on to an automatic switch which runs it, or them, successively back on the empty tracks.

35 The travel of the car haul or propelling device on the empty track is preferably relatively short, and it may be arranged to elevate the cars one at a time up a short incline, and to return idle and rapidly after each car is so elevated to take up the next succeeding car, the tracks being inclined sufficiently to permit the empty cars to run therealong and be strung together ready to be coupled into a train to return into the mine.

40 Referring now in detail to the embodiment of the invention illustrated by way of example in the accompanying drawings, the

car hauling and engaging device will be first described. As embodied, this device is adapted to run along a single rail, and the device and rail are so constructed and arranged that the rail not only supports 70 and guides the hauling device, but the hauling device is held down in position at all times by the rail, while being free to run therealong.

45 In this present illustrative embodiment, 75 a rail 1 is provided, which may be of ordinary I beam cross-section, and this rail may be laid down between the track rails, and may be spiked or otherwise fastened to the floor or ties 2 or other support for the track 80 rails.

50 The car hauling device comprises two plates 3 and 4, vertically disposed alongside, and extending upwardly above, the supporting and guiding rail 1. In the greater 85 part of their length the plates 3 and 4 are spaced apart to hold or include between them the wheels or rollers upon which the device runs and also to hold the car engaging device or dog. At each end the plates 90 3 and 4 are preferably bent inwardly with a double bend so that they are in contact with each other, as shown at 5 and 6 in Fig. 3. The hauling chains or cables, or equivalent device 7 may be fastened into apertures 95 8 in the ends 5 and 6 of the hauling device.

55 As embodied, the hauling device is supported and progressed along the rail 1 by two rollers or wheels 9 and 10 located, respectively, near either end of the device. 100 These rollers are rotatably mounted on spacing sleeves or bushings 11 and 12, respectively, against the ends of which sleeves the plates 3 and 4 abut, and are thus properly spaced apart. The sleeves 11 and 12 are 105 centrally internally longitudinally apertured, and bolts 13 and 14, respectively, pass through these apertures and through aligned apertures in plates 3 and 4. On bolts 13 and 14 respectively are screw-threaded nuts 110 15 and 16, the bolts thus serving to hold the plates 3 and 4 together against the ends of the spacing sleeves 11 and 12, while the rollers 10 and 9, journaled on the sleeves, are free to rotate as the hauling device moves 115 along the rail 1.

60 In the embodied form of means for holding the hauling device down to the rail, there are provided near each end of the device, rollers 17 and 18, located on the inner side of the plates 3 and 4, and projecting inwardly beneath the top flange or tread 19 of the rail 1. The rollers 17 and 18, respectively, are mounted upon stub shafts 20 and 21, shouldered so as to hold the rollers journaled thereon, and they are also shouldered to pass through apertures in the plates 3 and 4, so that the rollers are held in position while being free to rotate. The shafts 20 and 21 are screw-threaded on 120 125 130 135 140

their exterior ends to receive nuts 22 and 23 to secure them in position. There are preferably a pair of these rollers at either end of the device. The hauling device is thus free to travel along the rail 1 upon the rollers 9 and 10, while the rollers 17 and 18 prevent the device lifting from the rail while not interfering with its travel along the rail.

Referring now to the embodied form of car engaging device or dog, that is, the device supported upon the foregoing structure which engages with the car to propel it along the tracks movable and preferably pivoted dog 28 is provided, having an upwardly projecting part 29 adapted to engage with some part of the car, such as a plate extending downwardly from beneath the car bottom. The dog has a tail 30, which acts as a restoring weight for the rocking dog, as later described.

The dog 28 is pivotally mounted on a spacing sleeve 31 extending crosswise between, and having its end abutting on, the inner sides of the plates 3 and 4. The sleeve 31 is internally centrally and longitudinally apertured and therethrough passes a bolt 32, which passes likewise through corresponding apertures in the plates 3 and 4. The bolt 32 takes a nut 33, the bolt thus serving to hold the plates 3 and 4 against the ends of the spacing sleeve 31, thus holding the plates together properly spaced apart, and leaving the dog 28 free to pivot on the sleeve 31.

As constructed, the dog 28 will rock from right to left in Fig. 2 to permit a car to pass going in the left hand direction, as shown in the dotted line position of Fig. 2. The dog 28, however, in the full line position of Fig. 2 is rigid against any movement to the right hand about its pivot, so that it will push any car engaged by the dog on the left hand side thereof in the left hand direction in Fig. 2. To facilitate a car passing the dog while traveling from right to left in Fig. 2 the end 29 of the dog is provided with a rear beveled face 34, against which the car may strike and thereby rock the dog to the dotted line position to permit the car to pass, as already explained.

A suitable stop to limit the rocking movement of the dog in this direction is provided by a bolt 35 passing through apertures in the plates 3 and 4 and provided with a nut 36. A similar stop with which the tail of the dog is adapted to engage is provided at the other side by a bolt 37 passing through the plates 3 and 4, and provided with a nut 38. The tail 30 is weighted or is sufficiently heavy to restore the dog to the full line position of Fig. 2 after the car has passed.

In accordance with certain features of

the invention, the cable or chain 7 may be driven in any suitable manner or by any suitable mechanism, but in accordance with one feature of the invention, the cable is wound slowly in the car hauling direction, 70 and is returned quickly in the opposite direction, and an embodiment of such driving means is provided for the cable (Figs. 7, 8, 9, 11 and 13).

In such embodied form, two cables or 75 like devices 7 are provided, one cable being attached to one end of the hauling device and winding upon a drum, while another cable 7 is attached to the other end of the car hauling device and simultaneously unwinds from a drum, during the car hauling movement in one direction, the winding and unwinding of the cables being reversed during the travel of the car hauling device in the opposite direction. In the embodied form, 80 two drums are employed, and incorporated therewith and with the driving mechanism therefor is the quick return feature for the car hauling device on its idle trip.

In Fig. 7 a train of loaded cars 45 is 85 shown on a track 46, in which track is located a car dump or tipple 47. In this illustrated application of the invention to a mine, the mine mouth is shown at 48, the loaded train, usually consisting of a large 90 number of loaded cars 45, is hauled out by a locomotive or other suitable means, and is left upon the track 46 for the cars to be dumped singly and then to be switched to another track and then made up into a 100 train of empty cars to be returned to the mine for reloading.

A single car hauling device is sufficient for the entire train, the device engaging with some part of the rear or any car of 105 the train, and pushing or pulling, or both the entire train forward slowly. The leading cars, one by one are detached from the front of the train, are run forward, and are dumped over the dump or tipple 47, and then are run back on to the empty track, 110 preferably by a suitably graded track provided with an automatic switch 49. The form of such a switch and graded track are well known. After all the cars in the 115 train have been dumped, the hauling device is returned to or near the point in its path of track nearest to the mine mouth ready to engage the rear car of a new "trip" or train of loaded cars.

Means are provided for guiding the hauling device and the cables around curves in the track, and for this purpose the plates 3 and 4 (Fig. 5) are provided at either end and on the inner sides thereof with inwardly extending bearing lugs 50, preferably with rounded points, adapted to bear upon the tread or flange 19 of the rail at either side thereof to prevent the device from binding or jamming on the curve of the rail. Suit- 120 125 130

able guiding pulleys 51 may be provided at convenient points along the curved track for the cables 7.

Referring now to the embodied form of driving means, a motor 60 is shown mounted on a bed 61. A beveled pinion 62 is fixed on the motor shaft. Beveled pinion 62 meshes with a beveled pinion 63 loose on a shaft 64, which shaft is supported in bearings 65 and 66 mounted upon the bed plate 61. Fixed to beveled gear wheel 63 is a gear wheel 67, which meshes with a gear wheel 68. Wheel 68 is mounted loosely on a shaft 69 which shaft is supported in bearings 70 and 71, mounted on the bed plate.

The beveled pinion 62 on the motor shaft meshes also with a beveled gear wheel 73, mounted loosely on shaft 64. Fixed to beveled gear 73 is a gear wheel 74, which 20 meshes with a gear wheel 75 likewise loosely mounted on shaft 69. Fixed on shaft 69 to rotate therewith is a drum 77, which is located close to and at one side of the gear wheel 68. Also fixed to shaft 69, at the 25 opposite side of gear wheel 75 and close thereto is a drum 78.

Mounted on shaft 69 to rotate therewith while being slidably therealong, and located between gear wheels 68 and 75, is a double cone clutch 80, which is slidable along the shaft 69 to pass alternatively into driving and engaging with either the gear wheel 68 or the gear wheel 75. Gear wheel 68 has fixed thereto on the side toward the clutch 80 a clutch member 81, and gear wheel 75 has fixed thereto on the side toward the clutch 80 a clutch member 82, both clutch members 81 and 82 cooperating alternatively with the clutch 80.

40 The manner of operation of the mechanism just described is substantially as follows:

When the motor is rotating in a given direction, gear wheels 67 and 74 are both rotated thereby, but in opposite directions, and consequently gear wheels 68 and 75 are likewise rotating in opposite directions, loose upon shaft 69. In Fig. 8 the clutch 80 is shown in neutral position, so that it is not in engagement with either of the driven gear wheels 68 or 75. If clutch 80 is moved into engagement with cooperating clutch member 81, the clutch 80 and both the drums 77 and 78 will be rotated in the same direction as the gear wheel 68, by reason of the clutch 80 being splined on shaft 69 and the drums 77 and 78 both being keyed to the shaft 69. If the clutch 80 be moved from the neutral position of Fig. 60 8 into engagement with the other cooperating clutch member 82, it will rotate in the opposite direction, and will cause both the drums 77 and 78 to rotate in the same direction therewith by reason of the gear wheel connections to shaft 69 already explained.

By reason of the difference in the gear ratios on two sides, gear wheel 68 will cause a relatively slow rotation of the drum, and gear wheel 75 will cause a relatively rapid rotation of the drum. The first is adapted for the slow moving of the loaded cars, and the latter is adapted for the quick return of the idle car hauling device.

While the mechanism may be controlled manually, means are provided for its automatic actuation and control by the cars, or a single car at proper points along the track, or such control may be exercised by the car hauling device itself.

In the embodiment of such means shown 80 in Fig. 11, the cable winding mechanism is reversed automatically by the hauling device 3 reaching a certain or predetermined point in its travel. In said embodiment the actuating means for the clutch 80 comprises a 85 yoked lever, having arms 88 and 89 fixed on a shaft 90, pivotally mounted on the bed plate 61. The lever arm 89 is provided with a handle 91, by which the clutch may be 90 operated by hand.

Pivoted to the arm 89 is a link 92, which is pivoted at its other end to one arm 93 of a bell-crank lever, which lever is pivotally supported at 94 upon the bed of the machine. The other arm 95 of the bell crank lever has a pin and slot connection 96 with an intermediate point on a rod 97. Rod 97 at one end is pivotally connected to a lever 98, which lever is pivotally supported at 99, and its free end 100 is arranged and positioned to be engaged by the hauling device 3.

At its other end the rod 97 is pivotally connected to a lever 101, which lever is pivotally supported at 102, its free end 103 being positioned and arranged to be engaged 105 by the car hauling device at the opposite end of its travel. By reason of the pin and slot connection and operating mechanism later described, when the hauling device 3 engages either one of the levers 98 or 101, 110 the clutch 80 is thrown from engagement with either gear wheel 68 or the gear wheel 75 past its neutral point and into engagement with the other of said gear wheels, thereby reversing the direction of travel of the car 115 hauling device 3. The mechanism of Fig. 11 is largely diagrammatic in character for the sake of clearness.

Means are provided as stated, for insuring the sliding of the clutch past its neutral point when passing from engagement with one of the gear wheels 68 or 75 into engagement with the other. As embodied, spring operated means are provided for this purpose. A form thereof is shown in Fig. 12, 120 including a double beveled lug 104 which is fixed to the lever 98 by means of a screw bolt 105. In such embodiment a like device is provided for lever 101, but a single description will suffice for both. Cooperating 125

therewith is a double beveled plunger 106, working in an interiorly apertured holder 107, which is fastened by bolts 108 to a suitable support 109. The plunger 106 is acted 5 on by a spring 110.

When the hauling device 3 engages the lever 98, the lever has a certain amount of free or idle motion, due to the pin being in the opposite end of the slot of the connection 10 96. During this idle motion, rod 97 is moved so that the pin is at the opposite end of the slot but without moving the bell crank lever 93, 95 and thus without moving clutch 15 80. The pin is in position, however, so that any further movement of the rod 97 will rock the lever 93, 95. At the same time the lug 104 has cammed the plunger 106 downwardly against the resistance of the spring 110, and the apices of lug 104 and plunger 20 106 are just passing each other. Just as they pass, the spring 110 forces plunger 106 upwardly, quickly throwing lever arm 98 for the remainder of its travel, and thereby 25 85 rocking bell crank lever 93, 95 and thus moving the clutch member 80 out of engagement with one of the gear wheels 68 or 75, past its neutral point, and into engagement with the other of said gear wheels thereby reversing the direction of winding of the 30 90 drums 77 and 78.

In Fig. 7 the car haul for the empty cars is shown with but a short path of travel, and the same arrangement is shown somewhat diagrammatically in elevation in Fig. 35 10. With this arrangement the car hauling device operates usually upon the successive cars singly, or in pairs running them up the incline 111, the cars accumulating on the track 112, to be made up into a train of 40 45 empties to be returned into the mine. In Fig. 13 a hauling device operating along two tracks 113 and 114 is shown, but driven by a single winding mechanism, the common cable 7 passing around a sheave 115.

In Figs. 1 and 6 the manner of cooperation of the hauling device with the mine car is shown. The mine car 116 has pairs of wheels 117 and 118, running respectively on track rails 119 and 120. The dog 28 engages with a plate 121 fixed to and extending downwardly from the bottom 122 of the car 123, the cooperation of the dog 28 and plate 121 being as already described.

It will be understood that departures may 55 be made from the details of invention as herein embodied and described within the scope of the appended claims without departing from the principles of the invention and without sacrificing its chief advantages.

What I claim is:

1. A car handling mechanism including in combination a car track, a car engaging and propelling device, and means for traveling the car engaging and propelling device 60

in both directions along the track in one direction at relatively high speed and in the opposite direction at relatively slow speed along the track.

2. A car handling mechanism including 70 in combination a car track, a car engaging and propelling device adapted to propel a car in one direction only along the track, and means for traveling the car engaging and propelling device in both directions and 75 at different speeds along the track.

3. A car handling mechanism including 80 in combination a car track, a car engaging and propelling device adapted to propel a car in one direction only along the track, and means for traveling the car engaging and propelling device in both directions along the track in one direction at relatively high speed and in the opposite direction at 85 relatively slow speed along the track.

4. A car handling mechanism including 90 in combination a car track, a car engaging and propelling device, means for traveling the car engaging and propelling device in both directions along the track in one direction at relatively high speed and in the opposite direction at relatively slow speed along the track, and means operating automatically to reverse the direction of travel 95 of the car engaging and propelling device.

5. A car handling mechanism including 100 in combination a car track, a car engaging and propelling device adapted to propel a car in one direction only along the track, means for traveling the car engaging and propelling device in both directions along the track in one direction at relatively high speed and in the opposite direction at relatively slow speed along the track, and means operating automatically to reverse the direction of travel of the car engaging and propelling device.

6. A car handling mechanism including 110 in combination a car track, a car engaging and propelling device, means for traveling the car engaging and propelling device in both directions along the track in one direction at relatively high speed and in the opposite direction at relatively slow speed along the track, and means for reversing the direction 115 of travel of the car engaging and propelling device.

7. A car handling mechanism including 120 in combination a car track, a car engaging and propelling device, means for traveling the car engaging and propelling device in both directions and at different speeds along the track, and means operated by the car engaging and propelling device to reverse the direction of travel of said device.

8. A car handling mechanism includ- 125 ing in combination a car track, a car engaging and propelling device, means for traveling the car engaging and propelling device in both directions along 130

the track in one direction at relatively high speed and in the opposite direction at relatively slow speed along the track, and means operated by the car engaging and propelling device to reverse the direction of travel of said device.

9. A car handling mechanism including in combination a car track, a car engaging and propelling device adapted to propel a car in one direction only along the track, means for traveling the car engaging and propelling device in both directions along the track in one direction at relatively high speed and in the opposite direction at relatively slow speed along the track, and means operated by the car engaging and propelling device to reverse the direction of travel of said device.

10. A car handling mechanism including in combination a car track, a car engaging and propelling device, means for traveling the car engaging and propelling device along the track in one direction at relatively high speed and in the opposite direction at relatively slow speed along the track, and means operated by the car engaging and propelling device reaching the end of its path of travel for reversing the direction of travel of the car engaging and propelling device.

11. A car handling mechanism including in combination a car track, a car engaging and propelling device adapted to propel a car in one direction only along the track, means for traveling the car engaging and propelling device along the track in one direction at relatively high speed and in the opposite direction at relatively slow speed along the track, and means operated by the car engaging and propelling device reaching the end of its path of travel for reversing the direction of travel of the car engaging and propelling device.

12. A car handling mechanism including in combination a car track, an auxiliary rail extending along the track, a car engaging and propelling device traveling along the rail, and means for traveling said device along the auxiliary rail at relatively high speed in one direction and at relatively slow speed in the opposite direction.

13. A car handling mechanism including in combination a car track, an auxiliary rail extending along the track, a car engaging and propelling device traveling along the rail adapted to propel a car along the track in one direction only, and means for traveling said device along the auxiliary rail at relatively slow speed in the car propelling direction and at relatively high speed in the idle direction.

14. A car handling mechanism including in combination a car track, an auxiliary rail extending along the track, a car engaging and propelling device traveling along the rail, means for traveling said device in both

directions along the auxiliary rail, and means operated by the car engaging and propelling device reaching a given point on the rail for reversing the direction of travel of said device.

15. A car handling mechanism including in combination a car track, an auxiliary rail extending along the track, a car engaging and propelling device traveling along the rail, means for traveling said device along the auxiliary rail at relatively high speed in one direction and at relatively slow speed in the opposite direction, and means operated by the car engaging and propelling device reaching a given point on the rail for reversing the direction of travel of said device.

16. A car handling mechanism including in combination a car track, an auxiliary rail extending along the track, a car engaging and propelling device traveling along the rail adapted to propel a car along the track in one direction only, means for traveling said device in both directions along the auxiliary rail, and means operated by the car engaging and propelling device reaching a given point on the rail for reversing the direction of travel of said device.

17. A car handling mechanism including in combination a car track, an auxiliary rail extending along the track, a car engaging and propelling device traveling along the rail adapted to propel a car along the track in one direction only, means for traveling said device along the auxiliary rail at relatively slow speed in the car propelling direction and at relatively high speed in the idle direction, and means operated by the car engaging and propelling device reaching a given point on the rail for reversing the direction of travel of said device.

18. A car handling mechanism including in combination a car track, a car engaging and propelling device, means for traveling the car engaging and propelling device, including a cable and a winding drum, means for rotating the drum in both directions to wind and unwind the cable, and means controlled by the travel of the car engaging and propelling device for reversing the rotation of the drum.

19. A car handling mechanism including in combination a car track, a car engaging and propelling device, means for traveling the car engaging and propelling device, including a cable and a winding drum, means for rotating the drum in both directions to wind and unwind the cable, and means controlled by the car engaging and propelling device reaching a given point in its travel for reversing the rotation of the drum.

20. A car handling mechanism including in combination a car track, a car engaging and propelling device, means for traveling

the car engaging and propelling device, including a cable and a winding drum, and means for rotating the drum relatively rapidly in one direction and relatively slowly in the opposite direction.

21. A car handling mechanism including in combination a car track, a car engaging and propelling device, means for traveling the car engaging and propelling device in both directions along the track, including a cable and a winding drum, and means for varying the speed of the drum.

22. A car handling mechanism including in combination a car track, a car engaging and propelling device, means for traveling the car engaging and propelling device in both directions along the track, including a cable and a winding drum, and means for rotating the drum relatively rapidly in one direction and relatively slowly in the opposite direction.

23. A car handling mechanism including in combination a car track, a car engaging and propelling device, means for traveling the car engaging and propelling device, including a winding cable and a winding drum, means for rotating the drum relatively rapidly in one direction and relatively slowly in the opposite direction, and means controlled by the travel of the car engaging and propelling device for reversing the rotation of the drum.

24. A car handling mechanism including in combination a car track, a car engaging and propelling device, means for traveling the car engaging and propelling device, including a winding cable and a winding drum, means for rotating the drum relatively rapidly in one direction and relatively slowly in the opposite direction, and means controlled by the car engaging and propelling device reaching a given point in its travel for reversing the rotation of the drum.

25. A car handling mechanism including in combination a car track, a car engaging and propelling device, means for traveling the car engaging and propelling device, a cable attached to one end of said device and a drum on which the cable is wound, a cable attached to the other end of said device and a drum on which the cable is wound, means for rotating the drums in both directions, and means for simultaneously reversing the direction of the drums.

26. A car handling mechanism including in combination a car track, a car engaging and propelling device, means for traveling the car engaging and propelling device, a cable attached to one end of said device and a drum on which the cable is wound, a cable attached to the other end of said device and a drum on which the cable is wound, and means for varying the speed of the drums.

27. A car handling mechanism including in combination a car track, a car engaging

and propelling device, means for traveling the car engaging and propelling device, a cable attached to one end of said device and a drum on which the cable is wound, a cable attached to the other end of said device and a drum on which the cable is wound, means for rotating the drums in both directions, and means for varying the speed of the drums.

28. A car handling mechanism including in combination a car track, a car engaging and propelling device, means for traveling the car engaging and propelling device, a cable attached to one end of said device and a drum on which the cable is wound, a cable attached to the other end of said device and a drum on which the cable is wound, and means for rotating the drums in one direction at relatively high speed and in the opposite direction at relatively slow speed.

29. A car handling mechanism including in combination a car track, a car engaging and propelling device, means for traveling the car engaging and propelling device, a cable attached to one end of said device and a drum on which the cable is wound, a cable attached to the other end of said device and a drum on which the cable is wound, and means controlled by the travel of the car engaging and propelling device for rotating the drums in both directions.

30. A car handling mechanism including in combination a car track, a car engaging and propelling device, means for traveling the car engaging and propelling device, a cable attached to one end of said device and a drum on which the cable is wound, a cable attached to the other end of said device and a drum on which the cable is wound, and means controlled by the car engaging and propelling device reaching a given point in its travel for rotating the drums in both directions.

31. A car handling mechanism including in combination a car track, a car engaging and propelling device, means for traveling the car engaging and propelling device, a cable attached to one end of said device and a drum on which the cable is wound, a cable attached to the other end of said device and a drum on which the cable is wound, means for rotating the drums in both directions, and means controlled by the travel of the car engaging and propelling device for simultaneously reversing the direction of the drums.

32. A car handling mechanism including in combination a car track, a car engaging and propelling device, means for traveling the car engaging and propelling device, a cable attached to one end of said device and a drum on which the cable is wound, a cable attached to the other end of said device and a drum on which the cable is wound, means for rotating the drums in both directions,

in combination a car track, a car engaging a car in one direction only along the track, and propelling device adapted to propel a means for traveling the car engaging and car in one direction only along the track, propelling device in both directions along means for traveling the car engaging and the track, and means operating automatically propelling device, a cable attached to one end of said device to reverse the direction of travel of end of said device and a drum on which the the car engaging and propelling device. 70

cable is wound, a cable attached to the 50. A mine car handling mechanism including in other end of said device and a drum on which the cable is wound, means for rotating the cable, means for operating automatically the car engaging and propelling device, automatically 75

10 traveling the drums in both directions, and means, eally engaging a mine car, means for travel controlled by the car engaging and propelling the car engaging and propelling device device reaching a given point in its in both directions along the track, and travel for simultaneously reversing the direction of travel of the drums. 80

15 45. A mine car handling mechanism including in combination a car track, a car mine cars are adapted to move, a car engaging and propelling device automatically 85

10 engaging and propelling device, means for eally engaging a mine car, means for traveling said car engaging and propelling device, means for reversing the direction of travel of the car engaging and propelling device. 85

20 51. A mine car handling mechanism including in combination a car track, a car device in both directions along the track, and means carried by said car engaging and means operated by the car engaging and propelling device and operating automatically propelling device to reverse the direction of travel of said device. 90

25 52. A mine car handling mechanism including in combination a car track, a car propelling device is moving in one direction, 90

30 and to move out of the path of travel of the car when moving in the other direction, engaging and propelling device, automatically 95

25 so as to permit said car engaging and propelling device to pass the car. 95

35 46. A mine car handling mechanism including in combination a car track, a car track, means for traveling the car engaging 95

30 engaging and propelling device in both directions along the track, and means operated by the car engaging and propelling device to reverse the direction of travel of said device. 100

35 device in both directions and at different speeds along the track, 100

40 47. A mine car handling mechanism including in combination a car track, a car engaging and propelling device automatically along the track, and means operated by the car engaging and propelling device to reverse the direction of travel of said device. 105

45 and propelling device is adapted to move, and propelling device in both directions, 105

40 means for traveling said car engaging and propelling device in both directions, a dog means operated by the car engaging and propelling device to reverse the direction of travel of said device. 110

50 48. A mine car handling mechanism including in combination a car track, a car engage a car and move the same when said car engaging and propelling device is moved, 110

45 car engaging and propelling device is moved, and means for supporting the car engaging and propelling device automatically along the track, and means for travel said dog whereby the same automatically 115

50 moves out of the path of travel of the car, engaging the car engaging and propelling device when the car engaging and propelling device is moved in the opposite direction so as to permit the same to pass the car. 115

55 49. A mine car handling mechanism including in combination a car track, a car engaging and propelling device automatically along the track, and means operated by the car engaging and propelling device reaching the end of its path of travel. 120

60 55. A mine car handling mechanism including in combination a car track, a car traveling the car engaging and propelling device automatically along the track, and means operated by the car engaging and propelling device to reverse the direction of travel of the car engaging and propelling device. 125

55 57. A mine car handling mechanism including in combination a car track, a car engaging and propelling device automatically along the track, and means operated by the car engaging and propelling device reaching the end of its path of travel, for reversing the direction of travel of the car engaging and propelling device. 130

65 59. A mine car handling mechanism including in combination a car track, a car engaging and propelling device automatically along the track, and means operated by the car engaging and propelling device. 130

56. A mine car handling mechanism including in combination a car track, a car engaging and propelling device automatically engaging a mine car and adapted to 70
propel a car in one direction only along the track, means for traveling the car engaging and propelling device in both directions along the track, and means operated by the car engaging and propelling device
10 reaching the end of its path of travel for reversing the direction of travel of the car engaging and propelling device.
57. A car handling mechanism including in combination a car track, an auxiliary rail 15
extending along the track, a car engaging and propelling device traveling along the rail, and means operating automatically for traveling said device in both directions along the auxiliary rail.
- 20 58. A car handling mechanism including in combination a car track, an auxiliary rail extending along the track, a car engaging and propelling device traveling along the rail, and means operating automatically for
25 traveling said device in both directions and at different speeds along the auxiliary rail.
59. A car handling mechanism including in combination a car track, an auxiliary rail extending along the track, a car engaging 30
and propelling device traveling along the rail adapted to propel a car along the track in one direction only, and a single mechanism for traveling said device in both directions along the auxiliary rail.
- 35 60. A car handling mechanism including in combination a car track, a car engaging and propelling device, and means for traveling the car engaging and propelling device, including a cable and a winding drum, and
40 automatically operating means for rotating the drum in both directions to wind and unwind the cable.
61. A car handling mechanism including in combination a car track, a car engaging 45
and propelling device, means for traveling the car engaging and propelling device in both directions along the track, including a cable and a winding drum, and automatically operating means for rotating the drum in both directions to wind and unwind the cable.
- 50 62. A car handling mechanism including in combination a car track, a car engaging and propelling device, means for traveling 55
the car engaging and propelling device, a car hauling cable attached to one end of said device and a drum on which the cable is wound, a car hauling cable attached to the other end of said device and a drum on which the cable is wound.
- 60 63. A car handling mechanism including in combination a car track, a car engaging and propelling device, means for traveling the car engaging and propelling device, a car hauling cable attached to one end of 65

said device, and a drum on which the cable is wound, a car hauling cable attached to the other end of said device and a drum on which the cable is wound and means for rotating the drums in both directions. 70

64. A car handling mechanism including in combination a car track, a car engaging and propelling device adapted to engage with cars when the device is traveling in either direction but to propel a car in one direction 75 only along the track, including a cable and a winding drum.

65. A car handling mechanism including in combination a car track, a car engaging and propelling device adapted to propel a 80 car in one direction only along the track, including a cable and a winding drum, and automatically operating means for rotating the drum in both directions to wind and unwind the cable. 85

66. A car handling mechanism including in combination a car track, a car engaging and propelling device adapted to propel a car in one direction only along the track, and automatically operating means for 90 traveling the car engaging and propelling device in both directions along the track, including a cable and a winding drum.

67. A car handling mechanism including in combination a car track, a car engaging 95 and propelling device adapted to propel a car in one direction only along the track, means for traveling the car engaging and propelling device in both directions along the track, including a cable and a winding 100 drum, and automatically operating means for rotating the drum in both directions to wind and unwind the cable.

68. A car handling mechanism including in combination a car track, a car engaging 105 and propelling device adapted to propel a car in one direction only along the track, means for traveling the car engaging and propelling device, a car-hauling cable attached to one end of said device and a drum 110 on which the cable is wound, a car-hauling cable attached to the other end of said device and a drum on which the cable is wound.

69. A car handling mechanism including in combination a car track, a car engaging 115 and propelling device adapted to propel a car in one direction only along the track, means for traveling the car engaging and propelling device, a car-hauling cable attached to one end of said device and a drum 120 on which the cable is wound, a car-hauling cable attached to the other end of said device and a drum on which the cable is wound, and means for rotating the drums in both directions. 125

70. A car handling mechanism including in combination a car track, a car engaging and propelling device adapted to propel a car in one direction only along the track, means for traveling the car engaging and 130

propelling device, a car-hauling cable attached to one end of said device and a drum on which the cable is wound, a car-hauling cable attached to the other end of said device and a drum on which the cable is wound, and means for varying the speed of the drums.

In testimony whereof, I have signed my

name to this specification in the presence of two subscribing witnesses.

MERITT HUTTON.

Witnesses:

E. K. DAVIS,

JOHN PEALE.
